UNITED STATES PATENT OFFICE.

WALTER J. HUNTER, OF PITTSBURG, PENNSYLVANIA.

ATTACHMENT FOR TRUNK-HANDLES.

No. 823,173.

Specification of Letters Patent.

Patented June 12, 1906.

Application filed August 2, 1905. Serial No. 272,391.

To all whom it may concern:

Be it known that I, WALTER J. HUNTER, a citizen of the United States, residing at Pittsburgh, in the county of Allegheny and State of Pennsylvania, have invented a new and useful Improvement in Attachments for Trunk-Handles, of which improvement the following is a specification.

My invention relates to improvements in trunk-handles and similar articles.

The object of my invention is to provide an attachment for handles attached to trunks, cases, boxes, &c., which will not only supplement and support the same when the article is being lifted or carried by the handles, but will also prevent the upward pressure from causing the handle to pinch against the sides of the trunk or box, and thus make it annoying to the party handling the same.

I accomplish the object of this invention by the novel construction hereinafter more specifically described, reference being had to the accompanying drawings, forming part hereof, in which—

Figure 1 represents a perspective view of an end portion of a trunk, showing the application of my improvement to the handle thereof. Fig. 2 is a perspective view of the handle attachment. Fig. 3 is a section through the handle and adjacent part of the trunk, showing the position of the attachment when the handle is pulled upward in the act of lifting the trunk or box. Fig. 4 is a perspective view of a modified form of handle attachment.

Referring to the drawings, 1 represents a trunk. 2 is the handle thereof, secured to the end thereof in any suitable manner. 3 is a support comprising a hook adapted to be inserted over the handle at the middle or center thereof, the lower end of said hook having thereto attached in any suitable manner a chain or other flexible attachment 4, the lower end of which is attached to a staple 5, secured in the end of the trunk.

In Fig. 4 is shown a modified form of my device in which the separable ends of the ring 8 is secured by the slip ring or loop 10. The lower end of said ring 8 is secured to the chain 9.

I claim as my invention and desire to secure by Letters Patent—

1. In a trunk-handle attachment or support, a hook adapted to engage over the handle of the trunk and a flexible cord or chain attached to the lower end of said hook and to the end of the trunk, substantially as described.

2. In a trunk-handle, the combination of a flexible handle attached to the end of a trunk and a flexible attachment removably secured thereto and to the end of the trunk, substantially as described.

In testimony whereof I have hereunto signed my name in the presence of two subscribing witnesses.

WALTER J. HUNTER.

In presence of—

CLARENCE A. WILLIAMS,
JOHN H. RONEY.
